KNOCK-RESISTANT MOTOR FUEL

Don R. Carmody, Newton, Iowa, assignor to
 Standard Oil Company, Chicago, Ill., a corpora-
 tion of Indiana

Application June 19, 1943, Serial No. 491,487

4 Claims. (Cl. 44—53)

This invention relates to a process of making motor fuels and particularly high knock rating motor fuel such as aviation gasoline engine fuel wherein fuels of high knock rating command a high premium. One object of the invention is to produce aviation fuel from hydrocarbon gases and methanol by a combined process of alkylation and etherization. Another object of the invention is to provide an aviation fuel containing both hydrocarbon alkylates and methyl tertiary butyl ether as the principal constituent. Another object of the invention is to carry out an alkylation process with a mixture of hydrocarbon gases commercially available from the cracking of heavy oils and removing therefrom the isobutylene, thereby diminishing polymerization and providing an alkylate fuel of higher knock rating. Still another object of the invention is to provide an aviation fuel giving high performance under supercharging conditions and having improved volatility as a result of the low boiling methyl tertiary butyl ether component.

The invention is illustrated by a drawing which shows diagrammatically an apparatus for carrying out the process. Referring to the drawing, sulfuric acid having a concentration of about 85 to 100 percent, and generally about 95 to 98 percent, is introduced by line 18 into alkylator 11. Simultaneously there is introduced into the alkylator by lines 12 and 13 liquefied hydrocarbon gases hereinafter described. The alkylator 11 is maintained under sufficient pressure, generally of the order of 100 to 200 pounds per square inch, to maintain the hydrocarbons in liquid condition. The alkylation reaction is conducted at a temperature in the range of about 30 to 150° F., preferably about 50 to 100° F. A high degree of agitation is provided by mechanical agitator 14.

Spent acid from the alkylator is conducted by line 15 continuously or intermittently to etherizer 16, also provided with a suitable agitator 17. Methanol is charged to the etherizer by line 18 and isobutylene-containing hydrocarbons by line 19. The etherization reaction is conducted at a temperature in the range of about 100 to 275° F., preferably at about 150° F. Sufficient pressure is employed to maintain the hydrocarbon gases and the reaction products in the liquid phase. The concentration of sulfuric acid in the etherizer is maintained in the range of about 30 to 85 percent and preferably about 65 to 75 percent, the concentration of 70 percent H₂SO₄ based on the acid phase being satisfactory. The temperature of both alkylator and etherizer may be controlled by recycling the contents through external tem-

perature-controlling means (not shown), a cooler generally being required in the case of the alkylator and a heater in the case of the etherizer. Heat may also be supplied to the etherizer by introducing methanol in the form of heated vapors, or by heating the hydrocarbon stream introduced by line 18.

From the etherizer 16 reaction products are withdrawn by line 20 leading to neutralizer 21 in which the products are contacted with a solution of sodium hydroxide, sodium carbonate or other suitable alkaline material. From neutralizer 21 the neutralized reaction products are conducted by line 22 to debutanizer 23 wherein C₄ hydrocarbons and lighter products are withdrawn at the top by line 24 leading to fractionator 25, the principal function of which is to separate dimethyl ether from C₄ hydrocarbons. The dimethyl ether vapors are discharged by line 26 and may be withdrawn as a by-product of the process. However, it is preferred to condense the dimethyl ether in condenser 27 and receiver 28 whence the ether is conducted by line 29 back to etherizer 16, wherein it replaces part of the methanol used in etherizing isobutylene.

The C₄ hydrocarbons are withdrawn from the base of fractionator 25 by line 30 and pump 31 whence they are introduced to alkylator 11 by line 18. If desired, this fraction may be further separated into normal butane and isobutane, only the latter being recycled to alkylator 11.

Feed stock supplied to etherizer 16 may be commercially pure isobutylene or preferably an unsaturated C₄ hydrocarbon fraction obtained from the cracking of petroleum or from the dehydrogenation of a C₄ petroleum fraction. This unsaturated C₄ feed stock usually contains normal butane and isobutane as well as normal butylene and isobutylene. Because of the greater speed of the reaction between methanol and isobutylene, the isobutylene is preferentially etherized in reactor 16. Substantially complete etherization of isobutylene may be obtained by employing an excess of methanol. In this case provision may be made for recovering excess methanol from the reaction products by water washing, or it may be allowed to remain in the finished aviation fuel. In general, I prefer to employ about equimolecular amounts of methanol and isobutylene, in which case a small but unimportant amount of isobutylene will be polymerized in etherizer 16 and the remainder will be carried over to the alkylator through fractionators 23 and 25 by line 30 as hereinabove described. The remaining C₄ hydrocarbons pass through the

etherization reaction substantially unchanged and supply feed stock to alkylator 11. In addition to methyl tertiary butyl ether, smaller amounts of other mixed methyl ethers are obtained as well as some dimethyl ether. Mixed methyl ethers containing propyl, butyl or amyl radicals all boil within the gasoline boiling range and may be employed in the motor fuel but they do not all have the high knock rating of methyl tertiary butyl ether.

Unsaturated hydrocarbons are supplied to alkylator 11 by line 12 and for this purpose I may use propylene, butylene or amylene, or a mixed hydrocarbon gas fraction from the cracking of petroleum or the dehydrogenation of petroleum gases. A C₄ fraction identical with that supplied to etherizer 16 by line 19 is suitable. If desired, commercially available unsaturated C₄ hydrocarbon mixtures may be carefully fractionated to remove the isobutylene, isobutane and normal butylene-1, all boiling below the remaining C₄ hydrocarbons. This light C₄ fraction may be charged to etherizer 16 while the heavier C₄ fraction containing normal butane and butene-2 may be charged to alkylator 11.

The principal reaction occurring in alkylator 11 is the alkylation of isobutane and/or isopentane with olefins, particularly normal butylenes, although propylene and amylenes may also be present and serve to alkylate part of the isobutane and/or isopentane.

The alkylation products are withdrawn by line 32 and may be conducted directly by line 33 to neutralizer 21. A part or all of the alkylate stream may alternatively be conducted by line 34 to scrubber 35, wherein spent acid withdrawn from 16 by line 36 is contacted with alkylate for the removal of entrained hydrocarbons and dissolved ethers. From the scrubber the alkylate returns to line 33 by valved connection 37. Spent acid is withdrawn from scrubber 35 by line 38.

From the neutralizer 21 the alkylate now combined with the products from etherizer 16 undergoes fractionation in debutanizer 23 and is withdrawn along with methyl tertiary butyl ether by line 39 leading to rerun tower 40 wherein high boiling polymers and heavy alkylate undesired in the aviation fuel or motor gasoline are removed by line 41 and the desired motor fuel product is conducted by vapor line 42 to condenser 43 and receiver 44, whence the product is withdrawn by line 45. If desired, this fuel may be blended with other fuels and in the case of motor gasoline particularly, some butane may be added to increase the vapor pressure without exceeding the Reid vapor pressure specifications, generally about 9 to 12 pounds. Additional antiknock agent, particularly lead tetraethyl, may be added.

In order to prevent accumulation of normal butane, propane and similar light unreacted hydrocarbons in the system, especially when the desired fuel is for aviation use, a part or all of the alkylate is conducted by valved line 46 to stabilizer 47 from which propane and/or butanes are discarded by line 48 while the remaining

alkylate is conducted by line 49 back to alkylate line 33. If desired, alkylate may be withdrawn from the system by line 50. In order to avoid loss of isobutane from the system when discarding normal butane by line 48, this stock may be refractionated by means not shown and the isobutane returned to the system, preferably to alkylator 11.

Having thus described my process of making aviation motor fuel what I claim is:

1. The process of making motor fuel from a mixture of hydrocarbon gases containing normal butylene, isobutylene and isobutane obtained from the cracking of petroleum oils which comprises reacting said gases in an etherizing zone with methanol in the presence of sulfuric acid under conditions at which methyl tertiary butyl ether is formed from said isobutylene and methanol and normal butylene is largely unaffected, separating said methyl tertiary butyl ether from the unreacted gases, reacting the remaining gases containing normal butylene and isobutane in substantial amount in an alkylating zone with olefin hydrocarbons under alkylating conditions in the presence of sulfuric acid of 85 to 100 per cent concentration whereby said isobutane in said gases is alkylated by said olefins and transferring spent acid from said alkylating zone to said etherizing zone to effect etherization of further quantities of isobutylene therein.

2. The process of claim 1 wherein the alkylation products from said alkylating zone are united with the products from said etherizing zone to produce a motor fuel of high knock rating and satisfactory volatility.

3. The process of claim 1 wherein dimethyl ether produced as a by-product in said etherizing zone is separated from methyl tertiary butyl ether and unreacted gases and recycled to said etherizing zone.

4. The process of producing motor fuel of high knock rating which comprises alkylating isobutane in a first reaction stage with a light olefin hydrocarbon under alkylating conditions in the presence of sulfuric acid having a concentration between 85 and 100 per cent, separating the reaction mixture into an alkylate product layer and an acid layer consisting essentially of sulfuric acid and adsorbed hydrocarbons having the effect of substantially deactivating said acid for further alkylation, contacting said acid layer in a second reaction stage under etherizing conditions with methanol and a C₄ hydrocarbon mixture consisting substantially of isobutylene, normal butylene and isobutane, thereby producing a mixed methyl ether, maintaining the concentration of acid in said second stage within the range of 30 to 85 per cent, transferring unreacted C₄ hydrocarbons to said first reaction stage wherein said isobutane is alkylated with said light olefin hydrocarbon, recovering said methyl ether from said second reaction stage and combining it with the product of said alkylation from said first stage to produce the desired motor fuel.

DON R. CARMODY.
